UNITED STATES PATENT OFFICE.

WILLIS C. CHIPPS, OF SUFFERN, NEW YORK, ASSIGNOR TO EDWARD H. FALLOWS, OF NEW YORK, N. Y.

BACK FOR BRAKE-SHOES.

1,033,304.

Specification of Letters Patent. Patented July 23, 1912.

Application filed April 12, 1912. Serial No. 690,358.

To all whom it may concern:

Be it known that I, WILLIS C. CHIPPS, a citizen of the United States, and a resident of Suffern, in the county of Rockland 5 and State of New York, have made and invented certain new and useful Improvements in Backs for Brake-Shoes, of which the following is a specification.

My invention relates to reinforcing wrought metal or steel backs for brake shoes designed to be embedded in the rear face or back of the shoe as the same is cast, the general purpose of which back is to reinforce the shoe and hold the parts thereof together 15 should it become cracked or broken in use; and the object of my invention is to provide an improved back in which the advantages of a strong connection between the back and the lug, whereby the shoe is attached to a 20 brake head or equivalent support, and of a strong bond between the back and the body of the shoe, are secured to a degree not heretofore possible in a single back structure; so that in my improved back the key lug 25 on the one hand will not be likely to be pulled away or broken from the back, and the back, as a whole, on the other hand will not be likely to be pulled out or torn from the body of the shoe in which it is embedded.

It has heretofore been common to construct brake shoes with a steel back in the form of a plate and extending over the major portion of the rear face of the shoe, 35 in order to reinforce the same, and to securely hold the parts together should the shoe become broken or fractured in service. While this form of reinforcing back is sufficient for this purpose, yet difficulty has 40 been experienced in firmly securing or anchoring the plate to the shoe, it being the usual practice to provide an opening or openings in the plate for the purpose of allowing the cast metal to flow through the 45 same and assist in binding the parts together. Again, it has been proposed to employ a layer of expanded metal at or adjacent the back of the shoe for the purpose of reinforcing the same, but without success, 50 for while this form of reinforcement becomes firmly embedded or anchored in the cast metal, yet it is not possessed of suffi-

cient strength to hold the parts of the shoe together when cracked or broken, the constant bending of the cracked shoe causing 55 the expanded metal to also crack and break and allow the parts of the shoe to separate and fall to the track.

My present invention is designed to retain the advantageous features of the plate and 60 also those of the expanded metal as a reinforcing back, that is, to obtain in a single structure the strength of the plate and the bonding features of expanded metal, so that the reinforcing back will not only be 65 securely embedded and anchored at or adjacent to the rear face of the shoe, but at the same time will be possessed of sufficient strength to hold the parts of the shoe together should the latter become broken or 70 fractured.

With the above and other objects of invention in view, my invention consists in the improved back for brake shoes herein-after described and claimed, and in such 75 variations and modifications thereof as will be obvious to those skilled in the art to which the invention relates.

In the drawing wherein the preferred form of my invention is illustrated; Figure 80 1 is a top plan view of an unflanged brake shoe in which one of my improved backs is embedded; Fig. 2 is a view showing the same in side elevation; Fig. 3 is a view showing a section upon a transverse plane 85 indicated by the line 3—3, Fig. 2; Fig. 4 is a view showing my improved back separate from the brake shoe; Fig. 5 is a top plan view showing a flanged brake shoe in the rear face of which a slightly modified form 90 of my improved back is embedded; Fig. 6 is a view showing the same in side elevation; and Fig. 7 is a view showing a section upon a transverse plane indicated by the line 7—7, 95 Fig. 6.

Referring first to Fig. 4 of the drawing, the back of the shoe is shown as made up of a central portion 8 and two side portions 9. The attaching lug 10, whereby the brake shoe is supported from a brake head 100 or equivalent support, is secured to the portion 8 of my improved back in any suitable way, preferably by forming the lug with inturned hooks at its lower end to extend

beneath the side edges of the portion 8 of the back as illustrated in Fig. 3. In whatever way the attaching lug may be secured to the portion 8 of the back, it will be understood that an exceedingly strong joint may be secured between the lug and such portion, and a joint which will not be likely to become broken and the lug thus separated from the shoe when the shoe is in use; that is, the lug will be unlikely to tear away from the steel back and pull out of the shoe. The second portion 9 of my improved back is of such a character as to secure as great an area of contact as possible between the back 10 and the metal of the shoe in which it is embedded. This second portion of the back is therefore subdivided to a considerable extent, and made foraminous, in order that the metal of the shoe may flow about the back in a large number of places to thereby firmly embed it in the rear face of the shoe. I prefer to form this second portion of the shoe of expanded metal, as that term is understood in the arts, that is, to form it 15 by slitting the blank from which the back is formed and moving the parts thus cut free, laterally, to thereby increase the width of the back and increase the area thereof which will come into contact with the metal 20 of the shoe as the back is embedded therein during the manufacture of the shoe.

The portions 8, 9, lie side by side and extend longitudinally of the brake shoe when the back is embedded therein in the preferred embodiment of my invention illustrated in the drawings, and it will be further understood that the portions above referred to, considered together, form an integral or single piece back for brake shoes.

40 Fig. 1 of the drawing shows the back illustrated in Fig. 4 as embedded in the rear face of a brake shoe; and Figs. 2 and 3 show side and sectional views of the same, the reference character 11 in each instance illustrating the body portion of the shoe, and the reference character 12 designating lugs of the same material as the body portion of the shoe and which partially inclose the attaching lug 10, although this feature forms no 45 part of my invention.

In the form of my invention shown in Figs. 1 to 4, there is an expanded metal portion 9 upon each side of the central portion 10, this being a form which I prefer to employ with unflanged shoes. In adapting my improved steel back to flanged shoes, however, I prefer that the expanded metal portion, or portion whereby increased area of contact is secured as above explained, be located entirely to one side of the portion of the back to which the attaching lug is secured. This form of back, when used with flanged shoes, more effectively ties the flange portions thereof together, in case the shoe 60 becomes broken in use, while the portion

which is not expanded is located over the tread of the wheel at which place the attaching lug is secured.

In Figs. 5, 6 and 7, this second form of my invention is shown as embedded in the rear face of a flanged shoe, the reference character 13 designating the body portion of the shoe, 14 the flange portion thereof, and 15 an attaching lug whereby the shoe is secured to a brake head. The attaching lug is secured to the unexpanded portion 16 of the back in this form of my invention, and a second portion 17 of said back is shown as extending over the flanged portion of the shoe, this second portion being shown as in the form of expanded metal, the same as in the form of my invention shown in Fig. 4.

In whatever form my improved back may be made, I may, if desirable, provide the same with one or more large openings such as are shown at 18, Fig. 5, in order to secure a better bond between the portion of the back to which the lug is attached and the body of the shoe. These openings, however, will be limited in number, and will not be sufficient to seriously detract from the strength of the portion of the back to which the lug is attached, as one of the important features of my invention, as above explained, is to provide a back in which the portion to which the attaching lug is secured is made as strong as possible, while provision for an effective bond between the back and the body of the shoe as a whole is made by the foraminous or expanded metal portions of the back.

From the foregoing it will be understood that my improved back possesses all the advantages of a solid steel plate as well as those of expanded metal, the latter portions of the back tightly and securely anchoring it in place in the body of the shoe, and the solid or central portion of the back lending sufficient strength to the structure to hold the parts or segments of the shoe together should the latter become cracked or broken in service.

What I claim is:—

1. A back for a brake shoe comprising a plate, a portion of which is in the form of expanded metal.
2. A back for a brake shoe comprising a plate, one or more edges of which is in the form of expanded metal.
3. An integral back for brake shoes comprising two portions each extending longitudinally of the shoe and to one of which an attaching lug may be secured, the other of said portions being foraminous throughout its entire area to thereby increase the area of contact between said back and the metal of the shoe in which it is embedded.
4. An integral back for brake shoes comprising two portions lying side by side and to one end of which an attaching lug may

be secured, the other of said portions being foraminous throughout its entire area.

5. An integral back for brake shoes comprising two portions to one of which an attaching lug may be secured, the other of said portions being in the form of expanded metal.

6. An integral back for brake shoes comprising two portions each extending longitudinally of the shoe in which the same is

embedded and to one of which an attaching lug may be secured, the other of said portions being of expanded metal.

Signed at Mahwah, in the county of Bergen, and State of New Jersey, this 10th day of April, A. D. 1912.

WILLIS C. CHIPPS.
